UNITED STATES PATENT OFFICE.

HERBERT AUSTIN, OF BIRMINGHAM, ENGLAND, ASSIGNOR TO THE
WOLSELEY TOOL AND MOTOR CAR COMPANY LIMITED, OF BIR-
MINGHAM, ENGLAND.

VALVE AND IGNITION MECHANISM FOR INTERNAL-COMBUSTION ENGINES.

No. 819,116.

Specification of Letters Patent.

Patented May 1, 1906.

Application filed March 5, 1904. Serial No. 196,721.

To all whom it may concern:

Be it known that I, HERBERT AUSTIN, engineer, a subject of the King of Great Britain, residing at Berwood Grove, Chester Road, in the city of Birmingham, England, have invented certain new and useful improvements in Valve and Ignition Mechanism for Internal-Combustion Engines, of which the following is a specification.

10 This invention has for its object to combine with means such as those usually or frequently employed for mechanically operating the inlet-valve or the exhaust-valve of an internal-combustion engine means for igniting the charge (drawn into the motor-cylinder) through the medium of a low-tension current or circuit, the purpose in view being simplicity and economy in construction.

Broadly describing this invention, the cam 20 which operates the inlet-valve or the exhaust-valve through the medium of a rod, such as in the manner commonly or frequently employed, is adapted to insure a further movement of the rod in the direction it 25 has moved in allowing the valve to close, and this movement is utilized in connection with the operation of the make-and-break contact-piece of the igniter.

In carrying out this invention the cam is 30 formed with a depression or recess which, when the charge is ready for ignition, is in such position as to allow the rod to move nearer to the cam-axis than it has been moved in allowing the valve to close.

35 In the drawings herewith, which illustrate my invention, Figure 1 shows in elevation mechanism by which the inlet and exhaust valves of an internal-combustion engine are operated from a revolving counter-shaft 40 and shows also mechanism by which the igniter-arm is operated from the rod of the inlet-valve. Fig. 2 is an elevation taken at right angles to Fig. 1, showing the cam and rod through the medium of which the inlet- 45 valve is operated and the means by which the same are utilized in operating the make-and-break arm of the igniter; and Fig. 3 is a view corresponding to Fig. 2, showing the application of the invention in connection with 50 the exhaust-valve.

Referring, first, to the form of the invention shown by Figs. 1 and 2, A is the valve-rod, through the medium of which a cam B

on the counter-shaft C of the engine opens the inlet-valve D, the upper or outer end of the rod pressing for such purpose against one end of a lever E to press the other end of such lever against the upper or outer end of the valve-spindle a, all of which (except as to the special formation of the cam) is of the character of mechanism heretofore commonly employed for the purpose. According to this invention, however, the cam B is formed with a depression or recess b, which just as the charge is ready for ignition comes into 65 position to allow the rod A, which has of course already moved sufficiently toward the axis of the cam to have allowed the inlet-valve to close, to approach still nearer to such axis, being impelled in such direction, as before, by the spring c. A tappet d around the rod A, and which may conveniently be, as shown, the collar which receives the thrust of the lower or inner end of the spring c, presses, as the rod moves into the depression 75 b of the cam, against an arm e, fixed on a projecting end of a spindle f, which passes through the side of the combustion-chamber F and carries the contact making and breaking arm g. The arm e is held in its normal 80 position by a spring k, which presses the arm g upon or against the terminal.

Referring now to the forms of the invention illustrated by Fig. 3, the valve-rod A', through the medium of which the exhaust-valve D' is opened by a cam B' on the counter-shaft C, is pressed in a downward or inward direction toward the axis of the cam by a spiral spring c' within a box or hollow pillar G, through which the rod is a sliding fit. In this case also the cam B' is formed with a depression b' to allow of the further downward or inward movement of the rod A' after the valve D' has closed, and the rod has a tappet or collar d', which, as the rod moves inward after the valve has closed, operates the igniter through the medium of an arm e'. A backward extension e' of this arm is shown as connected by means of a rod with an arm on the outer end of the igniter-spindle g', so that when the arm e' is moved by the tappet d' an igniting spark will be produced.

It must be understood that the counter-shaft which carries the cam rotates at only one-half the speed of the engine-shaft, as is common in this class of engines, and by util-

izing this half-speed shaft a plain single cam may be employed. It will be noted that the rod which opens the valve, which latter may be the inlet-valve of the engine, is moving 5 in the proper direction to permit said valve to close when it breaks the sparking circuit, and the special recess in the cam assures that this circuit shall not be broken until after the said valve shall have closed.

10 Having thus described my invention, what I claim, and desire to secure by Letters Patent, is—

15 1. An internal-combustion engine, having a valve to be opened, a rod, slideable in guides, for opening the said valve, the guides for the rod, a cam for operating said rod to open the valve, said cam having in its operative edge a special recess, a spring which holds said rod in operative relation with the cam, a laterally-projecting part on the said slideable rod, a 20 fixed electric contact, a spring which holds said contacts normally in touch with each other, a movable contact-actuating arm in the path of said

lateral projection on the rod and adapted to 25 be actuated thereby when the spring on the rod moves the end of the latter into the recess in the cam to produce a spark between the contacts when said movable arm is actuated.

2. An internal-combustion engine, having 30 a valve to be opened, a rod A for opening said valve, a cam B for operating said rod to open the valve, said cam having a recess b, a spring c which holds said rod pressed up to the cam, a projecting part d on said rod, a 35 rocking spindle f, in the wall of the combustion-chamber, an arm e on said spindle in the path of the part d, a fixed contact k, a contact-arm g on the spindle f, and a spring h which keeps the contacts normally in touch 40 substantially as and for the purpose set forth.

In witness whereof I have hereunto signed my name, this 24th day of February, 1904, in the presence of two subscribing witnesses.

HERBERT AUSTIN.
